UNITED STATES PATENT OFFICE.

THOMAS CONSENTINO AND FRANK PALUMBO, OF PHILADELPHIA,
PENNSYLVANIA.

TYPE-WRITER.

SPECIFICATION forming part of Letters Patent No. 691,601, dated January 21, 1902.

Application filed September 21, 1901. Serial No. 76,030. (No model.)

To all whom it may concern:

Be it known that I, THOMAS CONSENTINO, a subject of the King of Italy, (but having declared my intention of becoming a citizen of the United States,) and I, FRANK PALUMBO, a citizen of the United States, both residing in the city and county of Philadelphia, State of Pennsylvania, have invented, jointly, certain Improvements in Type-Writers, of which the following is a specification.

Our invention relates to certain improvements in type-writing machines, and more particularly to a type-writer rule, the object of the invention being to provide a simple, inexpensive, and easily-manipulated device, by which any desired characters may be printed upon a sheet of material. This object we attain as hereinafter set forth, reference being had to the accompanying drawings, in which—

Figure 1 is a plan view of our improved type-writer rule, the top plate thereof being removed, so that the mechanism may be clearly visible. Fig. 2 is a vertical sectional view on the line 2 2, Fig. 1. Fig. 3 is a view of the right-hand end of the type-writer rule. Fig. 4 is a view of the left-hand end of the type-writer rule. Fig. 5 is a vertical sectional view taken on the line 5 5, Fig. 1. Figs. 6, 7, and 8 are views of certain detailed parts of our invention.

In the above drawings, A is the foundation plate of the device, from which project vertical plates E, D, and C, joined at the top by a second horizontal plate B, in addition to which are two vertical projections a^3 and a^2 , of which there is one at each end of the plate A. Two of these plates E and D are near together at one end of the plate A, and there are five rotatable shafts H, I, J, L, and M, supported in bearings and extending between these two plates and the plate C. Two of these shafts—viz., L and M—are vertically over one another and at the back of the machine, while the two shafts I and H are similarly in the same vertical plane in the front of the machine, the shaft J being in the same horizontal plane as the shaft I. The two shafts L and I are each provided with a double screw-thread for the greater part of their length, as shown in the figures, and the shaft

M is formed with two flat plates or vanes m , intersecting at right angles along its length, forming what we term the "paddle-shaft." Supported between the plates D and E is a 55 comparatively large gear-wheel e , and this wheel meshes with pinions l and i' on the ends of the screw-shafts L and I. In addition to the pinion l the shaft L carries a pinion l' on its outer end, said end being overhung beyond the plate E for a distance equal to the thickness of a gear-wheel v' , which is supported on a shaft V, carried in suitable bearings in the said plate E and in a projection E' from the plate A. This shaft V is made 60 square, and the gear-wheel v' is free to move laterally thereon, although there is a spring v^2 always tending to keep said gear-wheel pressed against the plate E. There is also a pinion v on the shaft V, which is engaged by 65 a rack x' , forming part of a Z-shaped plunger X, the said plunger being carried in a cylindrical guide-piece x^2 and having a second rack x^3 placed to engage a pinion g on a shaft G. Within the cylindrical casing x^2 is a 70 spring x^4 , acting against a collar x^5 , fixed to the stem of the plunger proper, the said spring tending to always keep the plunger in the highest position of its stroke, the said plunger having a head x^6 fixed to its upper end. 75 The shaft G is supported on suitable projections from the plate A and has fixed to it a beveled gear-wheel g' , which meshes with a second bevel-gear f on a squared shaft F. Laterally movable on said shaft is a roller f^2 , 80 around which passes an endless band N, having on its outer surface two or more series of characters, as hereinafter described. This band passes around a second roller f^3 , which in turn is carried by a shaft F'. The details 85 of the roller-supporting mechanism are shown in Fig. 7 of the drawings, there being a sleeve f^4 , preferably formed integral with the roller f^2 and like it made to fit the squared shaft F. A second sleeve f^5 is placed over the cylindrical outside surface of this sleeve, the same being provided with a rack f^6 , preferably on its under surface. Meshing with this rack is a pinion j^2 , fixed to the shaft J. The roller f^3 is constructed similarly to the roller f^2 , 90 having, like it, mechanism whereby it may be moved laterally by rotation of the shaft J. 95 100

Fixed to the projection from the frame A, which carries one end of the shaft F, is a spring-pawl a^5 , and there is a toothed wheel f^7 fixed to said shaft so as to be engaged by 5 the said pawl. A gear-wheel j is carried by the right-hand end of the shaft J, the said end being squared so as to permit a lateral motion of said shaft in its bearings under the action of a screw j' at its other end. This is 10 threaded and passes through a correspondingly-threaded hole in the vertical plate C, a form of construction similar to that adopted for the support of the right-hand end of the shaft H, as shown at h' in Fig. 1. The said 15 end of the shaft H carries a small disk h^2 , placed in a recess in the vertical plate E, the whole being so constructed that a lateral motion of the shaft H toward the right would cause said wheel h^2 to push the gear-wheel v' 20 into engagement either with the pinion l' or the gear-wheel j . Similarly the lateral motion of the shaft J causes it to push against a gear-wheel i on the square end of the screw-shaft I, in turn causing the said gear-wheel 25 to move from its normal position adjacent to the vertical plate C along its shaft and against pressure exerted by a spring i^2 thereon. There is a spring h^3 , having one end fixed to the bearing-plate for the shaft F' and its 30 other end fixed on the shaft H, which always tends to turn said shaft into its original position after it has been revolved by means of a plunger K, as hereinafter described.

There is a pinion h^4 on the shaft H just in 35 side the plate C, and this is engaged by a rack k , formed on the end of the plunger K. The latter is provided with a head k' and guided by a cylindrical piece carried on projections from the said vertical plate. As shown in 40 Fig. 4, there is a nick or depression k^2 in the stem of the plunger K, and a spring-tooth k^3 is fastened to the guide-piece and placed so as to engage with said nick when the plunger has been pushed inwardly for a distance sufficient to bring the gear-wheel v' into mesh 45 with the gear-wheel J. A second plunger Y is similarly carried in a cylindrical guide-piece y , supported on projections from the plate A, it having a head y' and a collar y^2 fixed to 50 it, this being pressed against by a spiral spring y^3 within its cylindrical guide-piece. The lower end of said plunger consists of two rectangular or frame-like pieces y^4 and y^5 , one of these, as y^4 , being integral with the 55 plunger and the other being held thereto by collars y^6 . Extending along opposite sides of this frame and within the same are two rack-pieces p' , each having teeth slanted in an opposite direction to those of the other and 60 yieldingly supported on corrugated spring-pieces p^3 , the frame containing said pieces and racks being flanged on one side, the said flange, with the second frame-piece y^5 , serving to retain the various parts in their correct 65 position.

The above-described frame extends around a pinion p , fixed to a shaft P, to which are

also fixed three disks p^3 . These disks are rigidly connected to each other, or they may, if desired, consist of a single piece, being provided, however, with three sets of gear-teeth extending around their peripheries for different distances, the three sets, however, all starting from the same point on the disks. There is a gear-wheel m^2 fixed to the left-hand end of the shaft M and of such size that it is engaged by the set of teeth upon the innermost of the disks p^3 when the latter is revolved. There are longitudinal slots a and b in the plates A and B, respectively, and these 75 extend almost the entire length of said plates. Through the slot b can be seen one series of characters upon the upper surface of the band N, the set of characters displayed, whether capitals, italics, &c., depending upon the position of the rollers f^2 and f^3 upon their respective shafts. It will be noted that in addition to having upon it three distinct series of letters or characters—as, for example, capitals, small letters, and italics—the said band 80 has two complete sets of each of the above series, one of said sets being merely painted or printed upon what is normally the upper surface of the band, while the other set is actual type suitably attached to what is normally its 85 under surface. One set of this type extends directly over the slot a in the plate A, and as the band is moved longitudinally all of the type are brought into contact from time to time with an inking-roller S. This is carried 90 on a shaft s , supported in suitable bearings in projections from the plate A.

Extending between the upper and lower lengths of the band is a hammer or striker R, the same having through it openings for the 95 passage of the shafts J and I, by which it is supported and guided. It will of course be understood that the opening through which the latter of these shafts passes is of a shape to accommodate the double thread on said 100 shaft, the striker being moved longitudinally when this shaft is rotated. The inwardly-projecting end of this striker R carries a block r^2 directly over the slot a in the plate A, the part r^2 , which carries said block, being 105 further extended to within the range of motion to the vanes m on the paddle-shaft M. The said extending portion r^2 is preferably made of spring material, so that when the shaft M is revolved the projecting paddles 110 raise the striker and as the revolution is continued allow it to drop with considerable force upon the type-carrying band. .

There is a block Q, having an extension q sliding upon the upper surface of the plate 115 B and formed into an index q' , as shown in Fig. 1. The shaft L passes through this block and similarly to the action of the shaft I upon the block R it causes the block Q to move longitudinally when it is rotated. The operation 120 of the device is as follows: The ink-roller being properly supplied with ink, the type-writer rule is grasped by the projections a^2 and a^3 and placed upon a sheet of paper,

book, or other surface on which it is desired to print or write. The head of the plunger X is now pushed down, thus turning the rollers f^2 and f^3 , and consequently the type-band, through the medium of the pinion g , shaft G, gear-wheels g' and f , and shaft F. The spring-pawl a^5 has a tendency to retain the toothed wheel f^1 , and consequently the shaft F, in every position which would permit a type to be directly under the striker, and the inward motion of the plunger is continued until the letter which it is desired to print, as shown on the upper surface of the band, comes opposite to the index q' , at which time the said spring-pawl aids in keeping the band stationary, making it unnecessary for the pressure on the plunger X to be kept absolutely uniform. When this condition is secured, the type corresponding to this letter or character has been brought under the striker, the machine having been adjusted to this end when its parts are assembled. While a slight pressure is exerted upon the plunger X to retain the band in the desired position, the plunger Y is in turn pushed down. This revolves the pinion p , and with it the three disks p^5 , in the direction indicated by the arrow in Fig. 4. The first action of the teeth on these disks is to engage the gear-wheel m^2 on the shaft M, giving it a rotary motion and causing the vane of said shaft to come into engagement with the end of the striker, first lifting said end and then releasing it as the revolution of the shaft is continued. The striker then comes into comparatively heavy engagement with the back or inside surface of the type-band, causing the type directly under it to be pressed against the material under it and printing a character thereon. As the plunger Y returns to its normal position under the influence of the spring y^3 the second set of the teeth p' , or those on the lower side of the frame y^4 , engage the pinion p , continuing its rotation until it has turned through three hundred and sixty degrees and in its movement has brought one of the sets of teeth on the disks p^3 into engagement with the gear-wheel i on the shaft I. The result of this is to give the said shaft a partial revolution, which in turn results in a moving forward of the striker R through a distance of one "space." The shaft L being connected to the shaft I by means of the pinions l , e , and i' , it also is revolved a similar amount and moves the index forward one space in the direction indicated by the arrow, Fig. 1. The two plungers are now released, and the springs within the cylindrical casings through which they pass immediately return said plungers to their normal position. Should it be desired to print small characters instead of capitals, the plunger K is pushed down, thereby turning the shaft H with the result of moving it longitudinally through the plate D by reason of the thread construction h' at its right-hand end. This longitudinal motion moves the gear-wheel v' on the shaft V, and

the plunger K is pushed down far enough to continue said motion until said gear-wheel is brought into mesh with the gear-wheel j on the shaft J. If now the plunger X be pushed down, its rack engaging the pinion v will cause the gear-wheel v' to be revolved, thereby also turning the gear-wheel j and moving the shaft J longitudinally through the plate C and moving the gear-wheel i on the squared end of the shaft I. This action will bring this latter gear-wheel into the plane of one of the disks p^3 , and, in view of the fact that the number of teeth on each disk corresponds to the predetermined spacing to be used between the various styles of characters, the revolution of the disk p^3 causes the shaft I to be turned sufficiently to move the striker this predetermined distance forward. By this manipulation of the plunger K in connection with the plunger X the gear-wheel i can be brought into the plane of any one of the said disks. The revolution of the shaft J imparts motion to the rack on the under side of the sleeves f^5 , so that as said shaft is moved in one direction or the other the rollers f^2 and f^3 , carrying the type-band N, move upon the shafts F and F', thereby bringing any one of the styles of type from which it is desired to print over the slot a on the plate A.

When the striker has reached the end of the line and it is desired to bring it back to the left end of the machine in order to begin a new line, the plunger K is pushed down until the shaft H has been revolved far enough to move the gear-wheel v' into mesh with the gear-wheel l' on the shaft L and then pushed downwardly to its full extent, revolving the screw-shaft L through the gears v , v' , and l' , and the screw-shaft I from the shaft L through its gears l , e , and i . The plunger X is then allowed to return to its normal position under the influence of the spring x^4 , the gear-wheel v' being first allowed to return to its normal position against the plate E under the action of the spring v^2 . This action revolves the shafts I and L in a direction opposite to that given them by the intermittent spacing-feed from the disks p^3 and returns the striker toward the left-hand end of the machine and the index correspondingly toward the right-hand end of the machine.

We claim—

1. The combination in a type-writing machine, of a supporting-frame, a band carrying type, a striker constructed to cause type on the band to make an impression on a sheet of material, with means for moving the type-carrying band in a substantially horizontal plane between said sheet and the striker, means for moving the striker forward in a line substantially parallel to the line of motion of the type-band and means for operating the striker, substantially as described.

2. The combination in a type-writing machine, of a supporting-frame, a type-carrying band, a striker constructed to cause type on the band to make an impression on a sheet of

material, means for moving said band longitudinally in a substantially horizontal plane, and means for moving it laterally, with mechanism for operating the striker, and means 5 for moving the striker forward in a line substantially parallel to the line of motion of the type-band after each stroke, substantially as described.

3. The combination in a type-writing machine, of a frame, a striker movable thereon, an endless band carrying type, extending in a horizontal plane between the striker and a sheet of material to be printed, means for moving the striker forward after each character 10 printed, means for moving the type-carrying band parallel to said sheet of material to change the character under the striker, and a pointer constructed to indicate upon said band the character under the striker, with 15 means for causing said striker to hit the type-carrying band, substantially as described.

4. The combination in a type-writing machine, of a frame, an endless band carrying type supported by said frame, a set of characters 20 on the band similar to the type, a striker, mechanism constructed to cause said striker to press the type on the band against a sheet 25 of material to be printed upon, and a pointer, with mechanism constructed to cause said 30 pointer to indicate upon the set of characters on the said type-band the letter or character of type simultaneously under the striker, substantially as described.

5. In a type-writing machine, the combination 35 of a frame, a striker and a type-carrying band, means for moving said band in a substantially horizontal plane between the striker and a sheet of material to be printed upon, a pointer constructed to indicate upon 40 the band the type under the striker, means for causing the striker to press the type under it against the material to be printed and means for moving forward the striker after it 45 has struck the band, substantially as described.

6. The combination in a type-writing machine, of a frame, a type-carrying band, a striker constructed to press a character on the band against a piece of material to be 50 printed upon, means for moving the band longitudinally, a shaft carrying a device constructed to engage the end of the striker and to afterward release it as said shaft is revolved, with means for moving forward the 55 striker after it has been engaged by the device on said shaft, substantially as described.

7. The combination of a frame, a striker and a pointer geared together so as to move in unison, a type-carrying band having on it 60 two sets of similar characters, means for moving the band relatively to the pointer and to

the striker, the characters being disposed on said band so that the pointer indicates the type under the striker, with means for moving the striker and pointer after each character 65 printed by the striker, substantially as described.

8. In a type-writing machine the combination 70 of a frame, a band carrying different styles of type, a striker for pressing the type against a sheet of material to be printed upon, means for operating the striker, means for moving the type-carrying band longitudinally, means for moving it laterally whereby any of the styles of type upon the band are 75 brought under the striker and means for simultaneously moving forward both the striker and the pointer after each operation of the striker, substantially as described.

9. The combination in a type-writing machine, 80 of a frame, a band carrying type having also on it a printed set of characters corresponding to the said type, said band being mounted on rollers, threaded shafts carrying a pointer and a striker respectively, the 85 pointer being placed to indicate the printed character corresponding to the type simultaneously under the striker, with means for revolving the rollers and for turning the said threaded shafts, substantially as described. 90

10. In a type-writing machine, the combination 95 of a frame, a threaded shaft and a paddle-shaft mounted thereon, rollers journaled on said frame, a type-carrying band supported on said rollers, a striker adapted to be moved horizontally by the threaded shafts, said striker being constructed to be engaged by the paddle-shaft and made to press against the type-band when said shaft is turned, with a device for turning the paddle-shaft and the screw-shafts and a second device for moving the type-band, substantially as described.

11. The combination of a frame, two screw-shafts mounted in bearings thereon, a band 105 carrying type, rollers supporting the same, a striker and a pointer constructed to be moved by the screw-shafts, reciprocable plungers mounted on the frame, gearing connecting the screw-shafts with one of said plungers 110 and means for operating the striker connected to another of the plungers, substantially as described.

In testimony whereof we have signed our names to this specification in the presence of 115 two subscribing witnesses.
